8 OXYGEN	It was known to the Chinese centuries before it was prepared by Priestley, an Englishman, in 1774. Oxygen is the most abundant element. It is nearly one fourth of the great ocean of air in which we live, and eight ninths of the weight of all waters of the earth. Sixty-five percent of the human body is oxygen.	8 OXYGEN

BOARD FOR PLAYING AN ATOM GAME

Earl D. Flickinger and Julius Foster, Oak Ridge, Tenn., assignors, by direct and mesne assignments, to The Atomic Games Company, Oak Ridge, Tenn., a partnership

Application December 26, 1945, Serial No. 637,149

2 Claims. (Cl. 273—135)

1.

This invention relates in general to games and in particular to a table game related to the field of nuclear physics.

Objects of the invention are to provide a novel game which is easy to play, interesting, exciting, and entertaining.

Another object is to provide a game that is highly educational in character in that through the incentive of game play, it teaches the nature and composition of the atoms of the various elements in an easy and interesting manner.

In general, the game involves the construction, or building up, of atoms of the different elements, on a playboard or other suitable surface, by the various participants as play ensues. The purpose of the game is to add protons $\oplus$, neutrons $\odot$ and electrons $\ominus$ to an atom diagram to complete an atom of a predetermined element. Each participant holds a card identifying a particular element and the participant holding the card for an element whose atom is completed on the playboard is judged to be the winner.

In the drawings accompanying the description of this invention, Fig. 1 is a plan view of a preferred embodiment of the playboard used in the game; Fig. 2 shows in plan and end elevation, and on an enlarged scale, the various types of playing pieces used; Fig. 3 is a table of the various elements or atoms known at the present time, the table containing information relating to the construction of each atom; Figs. 4 and 5 are enlarged views of typical atom blocks included in the table of Fig. 3; and Fig. 6 is a view of one of the cards of the set or deck used in playing the game.

Referring now to the drawings, the game includes a playing surface 1 which may be made in any suitable form such as for example a relatively stiff paper board or a sheet of durable paper. The surface 1 contains a plurality of concentric rings 2—8 inclusive, which are representative of the various electron orbits possible in any atom, and a center area 9 which is representative of the nucleus of an atom. The central area 9 is divided into a "neutron" section 10 and a "proton" section 11.

Within section 10 is a "neutron" table 10a representing the number of neutrons possible in any particular atom and this table is accordingly divided into one hundred forty-six different squares 12, numbered consecutively from 0 to 146, the highest number of course being the number of neutrons in either of the atoms neptunium or uranium.

Within section 11 is a "proton" table 11a representing the number of protons possible in any particular atom and this table is accordingly divided into ninety-four squares 13 numbered consecutively from 1 to 94, the highest number

obviously being the number of electrons in the atom plutonium.

The concentric rings 2—8 which represent the various electron orbits K to Q, respectively, are each provided with a plurality of small circles 14, each constituting a playing position. The number of circles 14 on each of the rings 2—8 is the same as the largest number of electrons which any present known atom may have in the orbit represented by such ring; the circles 14 of each ring have accordingly been equally spaced around the ring and so numbered. Thus, for example, ring 5 which identifies the "N" electron orbit contains thirty-two of the small circles 14 numbered in succession from 1 to 32.

In playing the game, which proceeds by way of adding neutrons, protons and electrons to complete the various atoms in the order of their atomic weight, a large quantity of playing pieces or discs 15, 16 and 17, as shown in Fig. 2 are used. These discs are of a size as to fit within each of the squares 12, 13 and the small circles 14 and may all be alike. However, it is preferred to make the neutron, proton and electron discs distinct from one another by suitable distinctive legends. Thus all of the discs 15 might carry the legend "neutron" and its corresponding symbol $\odot$; discs 16 the legend "proton" and symbol $\oplus$; and discs 17 the legend "electron" and symbol $\ominus$. Discs 15—17 are also preferably made from transparent plastic material (colored or uncolored) so that the player can more easily identify the number of the squares 12, 13 and circles 14 on which they are placed as the game ensues. Thus, the neutron discs may be formed from clear uncolored plastic, the electron discs of transparent red or blue plastic, and the proton discs of transparent blue or red plastic.

The game also includes an atomic table 18, preferably arranged as shown in Fig. 3, this table containing ninety-four blocks, there being a block for each of the different atoms known at the present time. Each of the blocks contains information relative to the composition of the particular atom as to the neutrons, protons and electrons in the atom which that particular block represents. In illustrating table 18 in Fig. 3, it has been necessary however to use a scale too small to permit all the information on the various atoms to be included. Accordingly, only some of the information is shown, reference being made to the enlarged views in Figs. 4 and 5 for illustration of all the information which would be contained within any block. Thus in Fig. 4 it is seen that block number 8 relates to oxygen, the information relative thereto being preferably arranged in the manner shown. Other arrangements of this information within the block are obviously possible. Fig. 5 illustrates a similar

arrangement of information relative to an atom having an isotope, such for example as columbium.

Information to be inserted in the other ninety-two squares of table 18 can be obtained from the following complete table of the atoms.

TABLE OF THE ATOMS

Atomic Number	Name	Symbol	Neutrons ⊕	Protons ⊕	Electrons ⊖	K	L	M	N	O	P	Q	Atomic Weight

94	Plutonium	Pu	145	94	94	94	2	8	18	32	18	12	245

The game could be played with but one of the tables 18. However, inasmuch as all players must have access to information regarding the number of neutrons, protons and electrons in each atom, and also the orbital arrangement of the electrons in the atom, it would be preferable to provide a plurality of the atomic tables 18 for use by a plurality (e.g., a like number) of players. Furthermore, since it is only necessary that the players each have information relative to the neutron, proton and electron arrangement of the atoms, the particular form used to convey this information is immaterial. Thus table 18 could be in the form as shown in Fig. 3, or as printed above in the specification, or take some other form.

In playing the game, a deck of ninety-four cards is used, there being one card for each different element. Each card has printed thereon the number and name of the element and may also include a short paragraph describing the history, properties and characteristics of the element. One of these cards, for the element oxygen, is illustrated in Fig. 6.

The game is or may be played according to the following directions, which directions for example could be in booklet form to accompany the game, or printed on the inside of the cover of a box containing the game:

After the deck of cards has been shuffled and one card dealt to each player, which card is kept secret, play begins with the first player to the right of the dealer. That player, using the play-pieces 15 and/or 16 places either a single proton play-piece 16 or two proton play-pieces 16 and two neutron play-pieces 15 in the neutron and proton tables 10a and 11a, respectively of the atomic diagram. Two protons and two neutrons constitute an alpha particle. Play proceeds to the right until each player has played once. During this first round only, succeeding players may choose between adding to the diagram another alpha particle or a single neutron play-piece 15, or a single electron play-piece 17 towards completion of the element which has an atomic number equal to the number of proton play-pieces 16 already placed in the table 11.

On the second round, each player adds or subtracts a single play-piece either a neutron or an electron to the atom which has now been determined by the total number of proton play-pieces placed in table 11a during the first round, and the moving is always in the direction of completion of the atom. The electron play-pieces 17 are placed in their proper orbits. If it becomes necessary to change the play-pieces 17 from one orbit to the other in passing from one atom to another as determined from the atomic table 18, this may be done without loss of move by any player.

After the atom, determined by the total number of proton play-pieces 16 added to section 11 during the first round is completed, any player holding the card for that particular atom wins the game. If no player holds the card for that atom, the one who last added a play-piece to complete the atom may elect to throw his card away and draw another, provided he recognized the fact that he completed the atom by calling the name of that atom before removing his hand from the play-piece. If he does not claim it, any of the other players may claim it and draw another card.

If the player draws a card lower than the number of proton play-pieces 16 already in the proton section 11, he may immediately throw that card away and draw again. If the card

drawn is for the atom just completed, that player wins.

After the draw by one player, play is continued exactly as before without removing any of the play-pieces 15, 16 and 17, with the first move being made, to start another first round, by the player to the right of the one who finished a previous atom. Again, the first player may add only a proton play-piece 16 or an alpha particle and the following players, for the new first round, may add either a single neutron play-piece 15 or a single electron play-piece 17 towards completion of that atom, or add an alpha particle. After the new first round, the atom which has been determined by the number of proton play-pieces 16 then in section 11 of the diagram must be completed.

Should a player hold a card for an atom which is skipped because of the addition of alpha particles, he completes an atom himself before he discards his now useless card and draws another.

As a modification, the game may be played with the deck of cards alone by allowing one player to read off from a card the description of the atom, after which the remaining players try to guess which atom that card represents.

As another modification, children may fill in the proper number of play pieces 15, 16 and 17 to make the various atoms in the matter of a jigsaw puzzle.

It might be desirable to also include with the game a short introductory article, which could be in the same booklet with the rules, to explain a few of the elementary facts relating to the field of nuclear physics in order that the players may play the game more intelligently and secure the maximum educational effect therefrom.

We claim:

1. In a game, a playing surface, one part of said surface denoting the nucleus of an atom and being divided into two numerically tabled sections to further denote the neutron and proton content respectively of said nucleus, and another part of said surface denoting the several electron orbits of an atom, each of the orbits of last said part having thereon a number of playing positions corresponding to the largest number of electrons which any presently known atom may possess in such orbit.

2. A playing surface as defined in claim 1 wherein the first mentioned part thereof is constituted by a hub area and the other part thereof includes a series of circles concentric with said hub designating said electron orbits.

EARL D. FLICKINGER.
